SYNCHRONOUS CONTROLS

Eric C. Wahlberg, Stamford, Conn., assignor to
Electrolux Corporation, Old Greenwich, Conn.,
a corporation of Delaware

Application September 6, 1943, Serial No. 501,405

19 Claims. (Cl. 172—293)

My invention relates to means for synchronously controlling the operation of a plurality of prime movers, such as the internal combustion engines on a multiengine aircraft.

More specifically, my invention relates to means for simultaneously adjusting the settings of the respective governors which control the speeds of the various engines. If the governors are of the conventional fly-ball type, they may be adjusted by varying the tensions on the 10 speeder springs thereof. The control of the engines by the governor may be in any known manner, such as by varying the throttle opening, or in the case of aircraft engines, preferably by varying the pitch of the propellers driven by the internal combustion engines.

Further objects and advantages of my invention will be apparent from the following description considered in connection with the accompanying drawing, which forms a part of this specification and of which:

Fig. 1 is a schematic wiring diagram illustrating a preferred embodiment of my invention;

Fig. 1a is an explanatory key showing the relay coils and contacts of Fig. 1, the contacts being aligned vertically in Fig. 1a with the coils which operate them, and the coils and contacts in Fig. 1 being aligned horizontally with the corresponding coils and contacts in Fig. 1a; and

Fig. 2 is a schematic wiring diagram of the electric motors shown in Fig. 1.

In Fig. 1 four magnetic relays and two thermorelays are schematically shown. The solenoids of the magnetic relays are designated by reference characters A, B, D, and F, while the heating coils of the thermorelays are designated by reference characters C and E. The various contacts forming part of the different relays are designated by the same capital letter which designates the coil of that relay with a number added thereto. Thus, the contacts actuated by the solenoid A are designated A₁, A₂, A₃, A₄, A₅, and A₆. Contacts which are normally open, that is when the coil of the relay is not energized, are shown as two rectangles separated from each other, while contacts which are normally closed are shown by two rectangles in contact with each other.

Reference characters 10 and 12 designate conductors for supplying suitable current for energizing the various relay coils. Conductor 12 is connected to a rotary motor-driven switch designated generally by reference character 14. This switch includes a rotatable disc 16 of insulating material carrying contact segments 18

and 20. A contact arm 22 is pivotally mounted concentrically with disc 16 but independently thereof, so that rotation of the disc does not pivot the arm and pivoting of the arm does not rotate the disc. Conductor 12 is connected to the arm 22, and this arm carries a contact point which may make contact with either the segments 18 or 20, or which may occupy a neutral or off position between the two segments.

Segment 20 is connected to one terminal of the solenoid A of a magnetic relay, the other terminal which is connected to the conductor 10. Likewise, the segment 18 is connected to one terminal of the solenoid B of a similar magnetic relay, the other terminal which is connected to the conductor 10.

One terminal of the heating coil C of a thermorelay is connected to conductor 12 and the other terminal is connected through normally open contact D₂ and normally closed contacts A₃ and B₃ in series to the conductor 10.

Normally open contacts D₁, A₂, and B₂ are connected in parallel between the conductor 10 and a conductor 28. The solenoid D of a magnetic relay has one terminal connected to the conductor 12 and the other terminal connected through the normally closed contact C₁ to the conductor 28. The heating element E of a thermorelay is connected between the conductors 12 and 28 with the normally closed contact F₂ in series therewith.

The normally open contacts A₁ and B₁ are connected in parallel between the conductor 10 and a conductor 26. The normally open contacts E₂ and F₁ are connected in parallel between the conductor 24 and a conductor 26. The solenoid F of a magnetic relay is connected between the conductors 12 and 26.

Reference characters 28 and 30 designate conductors for supplying direct current suitable for operating the motors to be hereinafter described. As here shown there are three motors having armatures 32, 34, and 36 and field windings 38, 40, and 42. Mounted on the shaft of each motor is a pair of slip rings 44, 46, and 48 respectively. These motors are of the type disclosed in my copending application Serial No. 428,018 filed January 24, 1942, and a schematic wiring diagram of two of them is shown in Fig. 2. As is illustrated, the slip rings of each motor are connected with taps on the armature winding, and the slip rings of the different motors are connected together in parallel. As is more fully explained in my above-identified application, when direct current is applied to the armature

windings through the slip rings, as by closing the switch 50 in its lower position, fixed poles are established in the armature which, in cooperation with the fixed poles normally established in the separately excited fields, serve to angularly position the armatures with respect to their respective fields, and hence to position them electrically with respect to each other. For running, the switch 50 is thrown to its upper position so as to supply current to the commutators of the motors in the usual manner. During running, the slip rings still being connected in parallel provide an alternating current circuit between the armatures of the motors and cause the motors to run in synchronism, as is also more fully explained in my above-identified application, as well as in my copending application Serial No. 472,464 filed January 15, 1943. The first of said copending applications shows a three-phase tie between the armatures, while the second shows a single-phase tie, which latter is the system illustrated in Fig. 2.

Referring again to Fig. 1, the shaft 32 of motor 32 carries a pinion 54 arranged to rotate the disc 16 of switch 14. The shafts 56 and 58 of motors 34 and 36 carry pinions 60 and 62, respectively, which drive racks 64 and 66 arranged to vary the tension on the speeder springs of centrifugal governors 68 and 70. These governors are driven in any suitable manner by the internal combustion engines 72 and 74. As shown, these are the engines of a two-engine aircraft, each engine driving a propeller. The governors are arranged to control the speeds of the respective engines in any well-known manner. In an aircraft this control is usually effected by varying the pitch of the blades of variable pitch propellers and such a control is diagrammatically illustrated in Fig. 1. The governor control per se is well-known and hence a detailed description thereof is not necessary, it being sufficient to state that an increase in the speed of an engine causes its governor to increase the pitch of the associated propeller, thereby increasing the load on the engine and slowing it down in order to maintain the speed for which the governor has been set. Heretofore, in order to change the speeds of the motors, it has been necessary to individually vary the governor settings and it is practically impossible, particularly during flight, to change the settings of the different governors equally so that all the engines will operate at synchronous speed. It is a chief object of this invention to provide means enabling the pilot to change the settings of all of the governors by equal selected amounts, thereby maintaining the engines in synchronism at all speeds.

The field windings 38, 40, and 42 of the electric motors are connected in parallel across the conductors 28 and 30 and a normally open contact D₃ is interposed in conductor 28 ahead of the field windings. The pairs of slip rings 44, 46, and 48 are likewise connected in parallel across the conductors 28 and 30 and in series with the normally closed contacts F₃ and F₄.

Normally open contacts F₅ and F₆ are interposed as shown in the conductors 28 and 30, respectively. The armatures 32, 34, and 36 are connected in parallel between conductors 76 and 78. Conductor 78 is connected to conductor 28 through the normally open contact B₄, and is connected to the conductor 30 through the normally open contact A₄. Conductor 78 is connected to the conductor 28 through the normally open contact A₄, and to the conductor 30 through the normally

open contact B₅. The conductors 76 and 78 are connected together through the normally closed contacts A₅ and B₅ arranged in series.

The above-described device operates as follows:

- 5 It is assumed that the engines 72 and 74 are running and the tensions on the speeder springs of the governors 68 and 70 are properly adjusted so that the engines are maintained at a predetermined synchronous speed. If one of the engines tends to run fast or slow with respect to this speed, its governor, in well-known manner, automatically changes the pitch of the propeller driven by this engine, increasing the pitch if the engine runs fast and decreasing it if the engine runs slow.
- 10 If the pilot wishes to change the synchronous speed at which the engines are running, he turns the contact arm 22 of the rotary switch 14 in one direction or the other. It will be assumed that he turns the arm 22 clockwise into contact with segment 20. As will be apparent hereinafter, the angle through which the arm 22 is turned determines the magnitude of the speed change.
- 15 Movement of arm 22 into contact with segment 20 energizes solenoid A, thus closing contacts A₁, A₂, A₄, and A₆, and opening contacts A₃ and A₅. Closing of contact A₂ energizes solenoid D, inasmuch as contact C₁ is normally closed, and consequently contacts D₁, D₂, and D₃ are closed. Closing of D₁ provides a holding circuit for relay D as long as C₁ is closed, and closing of D₂ does not heat thermal relay C inasmuch as contact A₃ was opened by the energization of solenoid A.
- 20 35 The closing of D₃ supplies current from the conductors 28 and 30 for exciting the fields 38, 40, and 42.

- 40 Inasmuch as contacts F₃ and F₄ are normally closed, current is also supplied to the pairs of slip rings 44, 46, and 48, and the armatures of motors 32, 34, and 36 are turned into the same angular positions with respect to their stationary fields and hence with respect to each other, as previously described. Ordinarily, if the system has been operating, the armatures will be in such positions, but particularly when the system is first placed in operation, one or more of the armatures may be a fraction of a turn out of proper position, and it is important that they be correctly positioned in order that they may start and run under load in perfect synchronism.

- 45 Closing of contact A₂ also completes the circuit through the heating coil of thermal relay E, inasmuch as contact F₁ is normally closed, but the resultant closing of contact E₁ is delayed a sufficient interval for the above-described positioning to take place. When E₁ does close, solenoid F is energized, because contact A₁ has been closed, with the result that contacts F₁, F₃, and F₄ are closed, and contacts F₂, F₅, and F₆ are opened. Closing of F₁ provides a holding circuit around contact E₁ for solenoid F, while opening of F₂ drops out thermal relay E. Opening of F₃ and F₄ interrupts the supply of direct current to the slip rings 44, 46, and 48, and closing of F₅ and F₆ supplies current to the commutators of motors 32, 34, and 36 through the already closed contacts A₄ and A₆, the contact A₅ having been opened to thus remove a short circuit. Although the contacts F₃ and F₄ are open, the slip rings of the motors are still connected together in parallel, and consequently the motors start and run in synchronism.

- 50 75 Rotation of motors 34 and 36 causes the pinions 60 and 62 to drive the racks 64 and 66 in synchronism.

nism so as to change by equal amounts the tensions of the speeder springs of the respective governors. If turning of the contact arm 22 into contact with segment 20 causes the motor to rotate in a direction which moves the racks to the right, as viewed in Fig. 1, this increases the tension. The engines 72 and 74 are hence running too slow for the new setting of the governors, and consequently the governors decrease the pitch of the respective propellers to thus reduce the loads on the engines, which permits the engines to come up to the desired speed.

At the same time, the motor 32, operating in synchronism with motors 34 and 36, is driving the disc 16 in a clockwise direction. Inasmuch as the contact arm 22 remains stationary, this rotation of the disc moves segments 20 and 18 until the insulated space between them comes into alignment with the arm, thus interrupting the circuit through the solenoid A. It will thus be seen that the farther arm 22 was originally moved, the longer it will take motor 32 to rotate the disc to its neutral or off position with respect to the arm 22, and consequently the longer the motors 34 and 36 will drive the racks 64 and 66, and hence the greater will be the change in engine speed effected thereby. Conveniently, suitable calibrations may be provided to indicate how far the arm 22 must be moved to effect a desired change in engine speed.

When the disc is rotated to de-energize the solenoid A, in the manner just described, the contacts A₁, A₂, A₄, and A₆ are opened; and the contacts A₃ and A₅ are closed. Opening of A₄ and A₆ interrupts the supply of current to the commutators of the motors 32, 34, and 36, while the closing of A₅ short circuits the armatures to provide dynamic braking, thus stopping the motors quickly.

Opening of contact A₁ de-energized solenoid F thus opening contacts F₁, F₅, and F₆ and closing contacts F₂, F₃, and F₄. The closing of contacts F₃ and F₄ applies direct current to the slip rings 44, 46, and 48, inasmuch as contact D₃ is still closed, and the field windings 38, 40, and 42 remain excited and hence the armatures of the motors, which are quickly decelerated by the dynamic braking, as above described, are stopped in the same positions relative to their stationary fields and consequently relative to each other. The closing of F₂ supplies current through contact D₁, which is still closed, to the heating coil E, but the subsequent closing of E₁ has no effect, as both contacts A₁ and B₁ are open.

Closing of contact A₃ causes current to flow through the heating coil C inasmuch as contact E₃ has not been opened and contact D₂ is still closed. After a predetermined interval, which is sufficiently long for the above-described stopping and positioning of the armatures to take place, contact C₁ is opened, thus de-energizing solenoid D. This opens contacts D₁, D₂, and D₃. Opening of D₂ cuts off the flow of current to the heating coil C, while opening of D₃ interrupts the supply of current to the field windings 38, 40, and 42 and to the slip rings 44, 46, and 48. As soon as the heating element C cools, contact C₁ closes, but in the meantime contact D₁ has opened and consequently the solenoid D remains unenergized.

Both the relay and the motor circuits are now open and the system is not operating.

If the pilot desires to slow down the engines 72 and 74, he rotates the contact arm 22 in a counterclockwise direction so as to bring it into

contact with segment 18, thus energizing solenoid B. The same sequences take place as occurred when solenoid A was energized, except that the contacts A₁, A₂, A₃, A₄, A₅, and A₆ remain as they are shown in Fig. 1, while contacts B₁, B₂, B₄, and B₆ are closed, and contacts B₃ and B₅ are opened. The result of this is the same, except that the closing of B₄ and B₆ reverses the polarity of the armatures of motors 32, 34, and 36 with respect to what it was when A₄ and A₆ were closed, and consequently the motors operate in the opposite direction. Motor 32 drives the disc 16 in a counterclockwise direction so as to bring the contacts 18 and 20 into their neutral position with respect to the arm 22, and the motors 34 and 36 drive the racks 64 and 66 to the left, as viewed in Fig. 1, so as to reduce the tension of the speeder springs in the governors 68 and 70. The governors are hence set to maintain a lower engine speed, and inasmuch as the engines are now running too fast with respect to this new setting, the governors increase the pitch of the respective propellers so as to slow down the engines.

When the disc 16 has been rotated a sufficient distance to open the circuit through solenoid B, the motors are dynamically braked and positioned in the same manner as above described.

Inasmuch as the motors always start, run, and stop in absolute synchronism, the changes in the settings of the several governors are always the same. Moreover, all the pilot has to do in order to change the speed of the engines is to turn the arm 22 to the proper point on one or the other of the scales on disc 16, which gives him the increase or decrease in speed desired. Thereafter, the system is fully automatic and requires no further attention on the part of the pilot until he again wishes to change the speed of the engines.

While I have shown and described a more or less specific embodiment of my invention, it is to be understood that this has been done for the purpose of illustration only, and that the scope of my invention is not to be limited thereby.

What I claim is:

1. In an electric system, an electric circuit, a plurality of electric motors synchronous throughout starting, running, and stopping connected to be controlled by said circuit, and switching mechanism having movable means for closing said circuit to energize said motors, one of said motors being drivingly connected to said switching mechanism and operative to open said circuit to de-energize said motors, said switching mechanism being so arranged that the distance said movable means is moved determines the extent of motor operation required to open said circuit.

2. In an electric system, a plurality of electric motors synchronous throughout starting, running, and stopping, and switching mechanism having means movable in one direction to energize said motors for forward rotation and movable in the other direction to energize said motors for reverse rotation, one of said motors being drivingly connected to said switching mechanism for operating the latter to stop said motors, said switching mechanism being so arranged that the distance the movable means is moved determines the extent of motor operation required to operate said mechanism to stop the motors.

3. In an electric system, a plurality of electric motors, an electric circuit, switching mechanism having movable means for closing said circuit, means responsive to the closing of said circuit for positioning the armatures of said motors with

respect to their fields, means operative after said armatures have been positioned to cause said motors to start and run in synchronism, one of said motors being drivingly connected to said switching mechanism and operative to open said circuit, and means responsive to the opening of said circuit for stopping said motors, said switching mechanism being so arranged that the distance said movable means is moved determines the extent of motor operation required to open said circuit.

4. In an electric system, a plurality of electric motors, an electric circuit, switching mechanism having movable means for closing said circuit, means operative by the closing of said circuit for causing said motors to operate in synchronism, one of said motors being drivingly connected to said switching mechanism and operative to open said circuit, and means responsive to the opening of said circuit for stopping said motors and for positioning the armatures thereof with respect to their fields, said switching mechanism being so arranged that the distance said movable means is moved determines the extent of motor operation required to open said circuit.

5. In an electric system, a plurality of electric motors, an electric circuit, switching mechanism having movable means for closing said circuit, means operative by the closing of said circuit for causing said motors to operate in synchronism, one of said motors being drivingly connected to said switching mechanism and operative to open said circuit, and means responsive to the opening of said circuit for dynamically braking said motors and for positioning the armatures thereof with respect to their fields, said switching mechanism being so arranged that the distance said movable means is moved determines the extent of motor operation required to open said circuit.

6. In an electric system, a plurality of electric motors, an electric circuit, switching mechanism having movable means for closing said circuit, means responsive to the closing of said circuit for positioning the armatures of said motors with respect to their fields, means operative after said armatures have been positioned to cause said motor to start and run in synchronism, one of said motors being drivingly connected to said switching mechanism and operative to open said circuit, and means responsive to the opening of said circuit for stopping said motors, and for positioning the armatures thereof with respect to their fields, said switching mechanism being so arranged that the distance said movable means is moved determines the extent of motor operation required to open said circuit.

7. In an electric system, a plurality of electric motors, two electric circuits, switching mechanism having means movable in one direction to close one of said circuits and movable in the other direction to close the other of said circuits, means responsive to closing of said one circuit for positioning the armatures of said motors with respect to their fields and means operative thereafter for causing said motors to start and run in synchronism in a forward direction, means responsive to closing of said other circuit for positioning the armatures of said motors with respect to their fields, and means operative thereafter for causing said motors to start and run in synchronism in a reverse direction, one of said motors being drivingly connected to said switching mechanism and operative to open whichever circuit has been closed by the movable means, and means responsive to the opening of either of said

circuits for stopping said motors, said switching mechanism being so arranged that the distance said movable means is moved determines the extent of motor operation in the respective direction required to open the respective circuit.

5. In an electric system, a plurality of electric motors, two electric circuits, switching mechanism having means movable in one direction to close one of said circuits and movable in the other direction to close the other of said circuits, means responsive to closing of said one circuit for positioning the armatures of said motors with respect to their fields and means operative thereafter for causing said motors to start and run in synchronism in a forward direction, means responsive to closing of said other circuit for positioning the armatures of said motors with respect to their fields and means operative thereafter for causing said motors to start and run in synchronism in a reverse direction, one of said motors being drivingly connected to said switching mechanism and operative to open whichever circuit has been closed by the movable means, and means responsive to the opening of either of said circuits for stopping said motors and positioning their armatures with respect to their fields, said switching mechanism being so arranged that the distance said movable means is moved determines the extent of motor operation in the respective direction required to open the respective circuit.

9. In an electric system, a plurality of electric motors, two electric circuits, switching mechanism having means movable in one direction to close one of said circuits and movable in the other direction to close the other of said circuits, means responsive to closing of said one circuit for causing said motors to operate in synchronism in a forward direction, means responsive to closing of said other circuit for causing said motors to operate in synchronism in a reverse direction, one of said motors being drivingly connected to said switching mechanism and operative to open whichever circuit has been closed by the movable means, and means responsive to the opening of either of said circuits for dynamically braking said motors and positioning their armatures with respect to their fields, said switching mechanism being so arranged that the distance said movable means is moved determines the extent of motor operation in the respective direction required to open the respective circuit.

10. A plurality of electric motors having fields and wound armatures, a pair of similarly located taps connected to each armature, conductors for connecting the taps of the different armatures in parallel, an electric circuit, switching mechanism including movable means for closing said circuit, relay means responsive to the closing of said circuit for applying direct current to said conductors to thereby position the armature of each motor with respect to its field, time delay relay means operative by the closing of said circuit to subsequently interrupt the supply of current to said conductors and to supply current to cause said motors to run, one of said motors being drivingly connected to said switching mechanism and operative to open said circuit, and relay means operative by the opening of said circuit for stopping said motors, said switching mechanism being so arranged that the distance said movable means is moved determines the extent of the motor operation required to reopen said circuit.

11. A plurality of electric motors having fields and wound armatures, a pair of similarly located taps connected to each armature, conductors for

connecting the taps of the different armatures in parallel, an electric circuit, switching mechanism including movable means for closing said circuit, relay means responsive to the closing of said circuit for supplying current to cause said motors to run, one of said motors being drivingly connected to said switching mechanism and operative to open said circuit, and relay means operative by the opening of said circuit for interrupting said supply of current and for supplying current to said conductors to thereby position the armature of each motor with respect to its field, said switching mechanism being so arranged that the distance said movable means is moved determines the extent of the motor operation required to reopen said circuit.

12. A plurality of electric motors having fields and wound armatures, a pair of similarly located taps connected to each armature, conductors for connecting the taps of the different armatures in parallel, an electric circuit, switching mechanism including movable means for closing said circuit, relay means responsive to the closing of said circuit for supplying current to cause said motors to run, one of said motors being drivingly connected to said switching mechanism and operative to open said circuit, and relay means operative by the opening of said circuit for interrupting said supply of current, for short circuiting said armatures to thereby dynamically brake said motors, and for supplying current to said conductors to thereby position the armature of each motor with respect to its field, said switching mechanism being so arranged that the distance said movable means is moved determines the extent of the motor operation required to reopen said circuit.

13. A plurality of electric motors having fields and wound armatures, a pair of similarly located taps connected to each armature, conductors for connecting the taps of the different armatures in parallel, an electric circuit, switching mechanism including movable means for closing said circuit, relay means responsive to the closing of said circuit for applying direct current to said conductors to thereby position the armature of each motor with respect to its field, time delay relay means operative by the closing of said circuit to subsequently interrupt the supply of current to said conductors and to supply current to cause said motors to run, one of said motors being drivingly connected to said switching mechanism and operative to open said circuit, and relay means operative by the opening of said circuit for interrupting the last-mentioned supply of current and for again supplying current to said conductors to thereby position the armature of each motor with respect to its field when the motors have stopped, said switching mechanism being so arranged that the distance said movable means is moved determines the extent of the motor operation required to reopen said circuit.

14. A plurality of direct current electric motors having fields, wound armatures and commutators, a pair of similarly located taps connected to each armature, conductors for connecting the taps of the different armatures in parallel, an electric circuit, switching mechanism including movable means for closing said circuit, relay means responsive to the closing of said circuit for supplying excitation current to said fields and for supplying direct current to said conductors to thereby position the armature of each motor with respect to its field, time delay relay means operative by the closing of said circuit to subsequently

interrupt the supply of current to said conductors and to supply current to said commutators to cause said motors to run, one of motors being drivingly connected to said switching mechanism and operative to open said circuit, relay means operative by the opening of said circuit for interrupting the supply of current to said commutators and for again supplying current to said conductors for positioning said armatures with respect to the fields, and time delay relay means operative by the opening of said circuit for subsequently interrupting the supply of current to said conductors and interrupting the excitation current, said switching mechanism being so arranged that the distance said movable means is moved determines the extent of the motor operation required to reopen said circuit.

15. A plurality of direct current electric motors having fields, wound armatures and commutators, a pair of similarly located taps connected to each armature, conductors for connecting the taps of the different armatures in parallel, two electric circuits, switching mechanism including means movable in one direction for closing one of said circuits and movable in the other direction for closing the other of said circuits, a commutator circuit, relay means responsive to the closing of one of said circuits for connecting said commutators to said commutator circuit with one polarity with respect to their fields, relay means responsive to the closing of the other circuit for connecting said commutators to said commutator circuit with a reversed polarity with respect to their fields, relay means responsive to the closing of either of said circuits for supplying excitation current to said fields and for supplying direct current to said conductors to thereby position the armature of each motor with respect to its field, time delay relay means responsive to the closing of either of said circuits for subsequently interrupting the supply of current to said conductors and for supplying current to said commutator circuit, one of said motors being drivingly connected to said switching mechanism and operative to open whichever of said circuits has been closed, and relay means responsive to the opening of either of said circuits for interrupting the supply of current to said commutator circuit and for interrupting said excitation current, said switching mechanism being so arranged that the distance the movable means is moved determines the extent of the motor operation required to reopen said circuit.

16. A plurality of direct current electric motors having fields, wound armatures and commutators, a pair of similarly located taps connected to each armature, conductors for connecting the taps of the different armatures in parallel, two electric circuits, switching mechanism including means movable in one direction for closing one of said circuits and movable in the other direction for closing the other of said circuits, a commutator circuit, relay means responsive to the closing of one of said circuits for connecting said commutators to said commutator circuit with one polarity with respect to their fields, relay means responsive to the closing of the other circuit for connecting said commutators to said commutator circuit with a reversed polarity with respect to their fields, relay means responsive to the closing of either of said circuits for supplying excitation current to said fields and for supplying direct current to said conductors to thereby position the armature of each motor with respect to its field, time delay relay means responsive to the closing of either of said circuits for subsequently interrupting the supply of current to said conductors and interrupting the excitation current, said switching mechanism being so arranged that the distance the movable means is moved determines the extent of the motor operation required to reopen said circuit.

of either of said circuits for subsequently interrupting the supply of current to said conductors and for supplying current to said commutator circuit, one of said motors being drivingly connected to said switching mechanism and operative to open whichever of said circuits has been closed, relay means responsive to the opening of either of said circuits for interrupting the supply of current to said commutator circuit and for supplying current to said conductors to thereby position the armature of each motor with respect to its field, and time delay relay means responsive to the opening of either circuit for subsequently interrupting the supply of current to said conductors and for interrupting said excitation current, said switching mechanism being so arranged that the distance the movable means is moved determines the extent of the motor operation required to reopen said circuit.

17. A plurality of electric motors each having a rotor winding and a stator winding, lines to be connected to a source of power, a switch, means responsive to closure of the switch to energize a first relay, means actuated when the first relay is energized to energize from the power lines both of the windings of each of the motors to position each of the rotors with respect to its stator, a time delay relay energized when the first relay is energized to cause a second relay to be energized, means actuated when the second relay is energized to keep the second relay energized regardless of the condition of the time delay relay and to de-energize the time delay relay and to change the mode of energization of one of the windings of each of the motors from the power lines to cause the motors to run in synchronism, and means responsive to the opening of the switch to de-energize both of the windings of each of the motors and to de-energize the first and second relays.

18. A plurality of electric motors each having a rotor winding and a stator winding, lines to be connected to a source of power, a switch, means responsive to closure of the switch to energize a first relay, means actuated when the first relay is energized to energize a second relay, means actuated when the second relay is energized to keep the second relay energized regardless of the con-

dition of the first relay and to energize the motors from the power lines to cause the motors to run in synchronism, means responsive to the opening of the switch to de-energize the first relay and to change the mode of energization of one of the windings of each of the motors from the power lines to cause the motors to synchronously decelerate and to come to rest with their rotors in like positions, a time delay relay which is energized when the second relay is energized and the first relay is de-energized for de-energizing the second relay, and means actuated when the second relay is de-energized to de-energize both the windings of each of the motors and to de-energize the time delay relay.

19. A plurality of electric motors each having a rotor winding and a stator winding, lines to be connected to a source of power, a switch, means responsive to closure of the switch to energize a first relay, means actuated when the first relay is energized to energize a second relay, means actuated when the second relay is energized to keep the second relay energized regardless of the condition of the first relay and to energize from the power lines both of the windings of each of the motors to position each of the rotors in like relative positions, a time delay relay energized when the first relay is energized to cause a third relay to be energized, means actuated when the third relay is energized to keep the third relay energized regardless of the condition of the time delay relay and to deenergize the time delay relay and to change the mode of energization of one of the windings of each of the motors to cause the motors to run in synchronism, means responsive to the opening of the switch to deenergize the first and third relays and to change the mode of energization of the one winding of each of the motors to cause the motors to synchronously decelerate and to come to rest with their rotors in like relative positions, a second time delay relay which is energized when the second relay is energized and the first relay is deenergized for deenergizing the second relay, and means actuated when the second relay is deenergized to de-energize both the windings of each of the motors and to deenergize the second time delay relay.

ERIC C. WAHLBERG.
